FIG. 1.

FIG. 4.

FIG. 5.

3.

INVENTOR:

THOMAS RHODUS,

By Robert Burns,
ATT'Y.

UNITED STATES PATENT OFFICE

THOMAS RHODUS, OF CHICAGO, ILLINOIS

RHEOSTAT

Application filed July 13, 1928. Serial No. 292,365.

This invention relates to that type of rheostats in which an annular core affords a support for a spiral winding of resistance wire to constitute one unit of the rheostat, the companion unit, usually the adjustable one, having movable electrical contact with the resistance windings of the first mentioned unit. And the present improvement has for its various objects:

- 10 To provide a structural formation and combination of parts (1) whereby the adjoining ends of a split ring supporting core carrying the resistance windings are coupled together in a secure and effective manner;
- 15 and (2) which in addition provides for the convenient, efficient and substantial support of an insulating nature for the respective terminal posts of the rheostat with a minimum loss of winding space; and (3) a like 20 insulated support for the bracket member which has attaching means and carries the adjustable unit of the rheostat.

To provide a structural formation and association of parts in the adjustable unit of 25 the rheostat in which, with a minimum diameter of the circular resistance carrying unit, a maximum diameter of the contact roller of the companion unit of the rheostat is attained in a simple and effective manner.

- 30 To provide a simple and effective means for securing the carrying shaft of the adjustable unit of the rheostat in its supporting bracket in a readily detachable manner; all as will hereinafter more fully appear.

35 In the accompanying drawing:

Fig. 1 is a plan view, partly in section on line 1—1, Fig. 2, of a rheostat embodying the preferred form of the invention.

Fig. 2 is a central sectional elevation on 40 line 2—2, Fig. 1.

Fig. 3 is a detail horizontal section on line 3—3, Fig. 2.

Fig. 4 is a detail elevation of the inset ends of the core band.

45 Fig. 5 is a detail of one of the connecting plates for the aforesaid core band.

Like reference numerals indicate like parts in the several views.

The resistance carrying unit of the rheostat structure shown, comprises a series of

windings 1 of resistance wire of a spaced and flattened spiral form resulting from the winding of the wire upon a supporting core, preferably composed of a split ring shaped band 2 of metal encased in a covering 2' of asbestos or like material.

A material part of the present invention involves means for securing the adjoining ends of the split ring shaped band 2 together in an effective and durable manner, and to such end comprises a construction and combination of parts preferably as follows:

Each end of the band 2 is formed with an outstanding prong 3 which is preferably of the flat and integral form shown, and formed by slitting the material of the band to form a tongue and then bending the tongue outward to constitute a prong 3. Each end of the curved band is bent inwardly and straightened and in addition is formed with a recess 4 and an orifice 5, both of a size sufficiently large to avoid conducting contact of the metal of the band 2 with the hereinafter described terminal screw bolts by which the band 2 and associated parts are connected together in assembled relation.

In connection with the described formation of the ends of the ring band 2 aforesaid, outer and inner connecting plates 6 and 7, of asbestos board or like insulating material are arranged to fit the straight flat ends of the band and to span the split of the ring 2, with one or both plates formed with orifices 6' adapted to receive and snugly fit the prongs 3 of the core band 2, to maintain the band 2 and also the ends of said band in proper working relation.

In addition the connecting plates 6, 7, are formed with orifices 7' in aligned relation with the recess 4 and orifices 5 of the band 2, and are of a diameter corresponding with that of the attaching screw bolts above referred to, so that there will be little if any play between the plates and the bolts. The described construction is intended to prevent any slip between the parts which would bring the terminal screw bolts above referred to into electrical contact with the metal of the band 2. In such construction the screw bolts 8 being the bolts above referred to, constitute

the respective terminal posts of the rheostat and are located near the edges of the band with a minimum loss of winding space. Such construction also affords a ready and substantial connection between the resistance carrying unit of the rheostat and the angle bracket 9 of the companion adjustable unit hereinafter described, and to such end the depending flange 9' of said bracket lays preferably against the outer connecting plate 6 and is formed with an orifice for the passage of the uppermost screw bolt 8 of the structure, so as to be firmly clamped in place by the attaching nut of said bolt. In the construction shown the respective connecting plates 6 and 7, extend a distance above the ring band 2 and have abutment against the under face of the main or horizontal rail of the bracket 9, with a view to prevent any lateral play of the bracket 9, with relation to the other parts of the appliance, and also to prevent any short circuiting connection between said bracket and the metal ring band 2.

The adjustable unit of the rheostat is revolvably mounted on the supporting bracket 9 above described, and to such end the main rail of said bracket extends in to the center of rotation of the adjustable unit and is provided with a journal hub 10 for the shaft 11 of the adjustable unit which in addition comprises parts as follows:

A rectangular yoke 12 has fixed attachment to the inner end of the carrying shaft 11, and in eccentric relation to said shaft in order that one end of the yoke will have nearer relation to said shaft than its other end, with a view to the use of the hereinafter described contact roller 13, with the same having a maximum diameter with relation to a minimum of the rheostat structure as a whole.

The end flanges 12' of the yoke 12 are formed with guide orifices for a sliding bar 14 adapted to move radially with relation to the central axis of the rheostat, and with said sliding bar having a normal outward tendency under the influence of a spring 15 associated with the bar 14 and yoke 12, as shown and as fully described in my former Patent No. 1,230,221 of June 19, 1917, and the contact roller 13 above referred to is revolvably mounted at the outermost end of the sliding bar 14 in any usual manner, preferably in the manner described in my aforementioned patent; and in order to provide for the above referred to maximum diameter of the contact roller 13, the said roller 13 is positioned between the windings 1 of the annular resistance unit and the short end of the yoke 12, being the end carrying the flange 12' nearest to the carrying shaft 11 above described.

In the construction shown, the main rail of the bracket 9 is adapted to be secured to the inner face of the dial plate or panel of

a radio receiving or like apparatus and to such end is provided with a pair of attaching orifices 16 preferably screw threaded, for the reception of the attaching screws used.

With such arrangement the outer end of the carrying shaft 11 passes out through an orifice on said dial plate or panel for operative association with a handle and a suitable pointer and dial for affording an accurate indication of the amount of resistance existing in the circuit.

The yoke 12 aforesaid has bearing against the inner face of the journal hub 10, and any inward slip in said journal of the shaft 12 having fixed association with said yoke, is prevented by removable spring ring 17 having engagement in a peripheral groove in said shaft at a point just outside the outer face of said supporting bracket 9.

I claim as my invention:

1. In a rheostat of the described construction, the combination of an annular supporting core for a resistance winding, said core comprising a metal band, a plurality of positioning prongs on said band, a connecting plate of insulating material provided with orifices for receiving said prongs, a bracket member of an angle-plate form providing a support for the adjustable unit of the rheostat, said bracket member having a depending portion fitting against the edge of said connecting plate of insulating material, a terminal bolt passing through said connecting plate and said bracket member, and means securing said parts in assembled relation.

2. In a rheostat, the combination of a resistance member having a flat curved band, a plurality of terminals arranged in a direction across the width of said band, an adjustable current carrying contact member making contact upon said resistance member and means connecting and holding said parts in operative relation.

In testimony whereof I hereunto affix my signature.

THOMAS RHODUS.
